Inventor

Hans Wiedemann

By B. Singe, Atty

UNITED STATES PATENT OFFICE.

HANS WIEDEMANN, OF BERLIN, GERMANY.

SHIP'S PROPELLER OF THE FLUID-OPERATED REACTION-TYPE.

Application filed December 26, 1924. Serial No. 758,275.

To all whom it may concern:

Be it known that I, HANS WIEDEMANN, a citizen of the Commonwealth of Germany and resident of Berlin, Germany, have invented certain new and useful Improvements in Ships' Propellers of the Fluid-Operated Reaction Type, for which I have applied for the following patents, in Germany, 28 May, 1923 (W. 63915 XI/65 f).

10 This invention relates to ships' propellers and has for its object to provide an improved propeller of the kind in which fluid under pressure is forced through one or more nozzles or openings at the stern of the ship.

Propeller arrangements of the above mentioned kind are known which are based upon the reaction of water expelled rearwardly through stationary or movable nozzles. Arrangements are also known for driving screw propellers by means of reaction nozzles fed by pressure-water.

The essential feature of the present invention consists herein, that a cylindrical hollow body rotatably supported after the manner of the boss of a screw propeller is provided with spirally arranged exit slots and is fed with water under pressure.

The operation is explained somewhat as follows: With the usual jet-propellers the particles of water issuing from the slots always strike one another in the previously expelled jet and thereby produce an only slightly operative jet which is somewhat thin and is shot at high velocity towards the rear; in the present case on the other hand, the particles of water strike repeatedly upon stationary water particles and thereby experience a powerful stemming or heaping-up action which produces very high water pressures the power action of which can be completely utilized as a propeller. Experiments have shown that the thrust of such a propeller, which is very small in air (namely, only equal to the power corresponding to the speed of the same amount of water), is increased several times upon immersing the propeller in water, which apparently is due to the stemming action obtained in water, and produces as a final result a slowly escaping jet having a cross section many times as great as the cross section of the propeller, with a corresponding efficiency.

55 With this propeller, if the paths of the jets are directed oppositely to the direc-

tion of travel, proper to the angle of inclination of the water jets, the reaction causes a rotation which apparently is essential for the production of the stemming effect and the reaction thrust upon the propeller body; by controlling this rotary movement various degrees of thrust and speed of travel can be obtained, as may be desired. For instance, by holding the propeller stationary, against its tendency to rotate, by means of a brake for example, the forward components produced by the rotation of the spiral slots are neutralized, so that a greater absolute rearward component of the velocity of the jet is produced which is available for a greater speed of travel of the ship. The adaptability of the propeller in fact extends further; for instance, the propeller can be driven in the opposite direction to its above mentioned inherent tendency to rotate, as in the case of a screw propeller the blades of which are replaced by the spiral slots. In this case, a further increase is obtained of the rearwardly directed speed component, corresponding to a further increase of speed of travel of the ship.

The rotary drive can be provided by mechanical means as in the case of the usual propellers; it can also be produced by water turbines with guiding and rotary blading, or by reaction nozzles which may be provided on the propeller so as to set it in rotation by means of the propelling pressure-water, in which case the usual shaft duct can also be dispensed with.

A constructional example of the invention is illustrated in the accompanying drawings, in which—

Fig. 1 is a longitudinal section of one form of the improved propeller with spiral slots, having sloping and rearwardly directed passages, in conjunction with a driving water-turbine;

Fig. 2 is a cross section through the turbine blading, looking towards the rear, on the plane indicated by the line II—II of Figure 1.

Fig. 3 is a similar view on the plane indicated by the line III—III of Figure 1.

From the body 1 of the boss issue quantities of water through the spiral slots 2 the water being supplied thereto through a supply pipe 3 by a centrifugal pump 5 driven by a motor 4, and issuing in fan-like jets in such a manner as to form helical surfaces.

Supposing that the axial cross-sections of the slots 2 are radially directed and the propeller is rotated in the forward direction (in the sense of a driving screw the blades 5 of which are to be imagined as replaced by the issuing water fans), the water particles passing out through the slots would receive a rearwardly directed component of motion due to the spiral form of the slots, and this 10 component produces propulsion. For the purpose of making use of this in the most advantageous manner the slots should be rearwardly directed as shown. This provides at the same time a further rearward 15 component producing a propulsive effect by immediate reaction. In consequence of this sloping direction, however, a tangential reaction component is produced which sets the propeller in rearward rotation, that is, 20 opposite to that mentioned above.

With an arrangement of the kind described above the following conditions are found to be present. In consequence of the slots the outer masses of water enter all parts 25 of the slots in an unused condition, that is not yet forced into jets, whether the propeller is at rest or rotating forward or backwards; the said water produces in the slots a stemming action giving a powerful propelling effect, and flows off rearwardly in 30 a strong current of but slight speed. The most favourable action in this case, according to experiments which have taken place hitherto, appears to occur when the propeller is left free to its own inherent rotation. 35

In practically carrying out the invention the propeller body 1 is closed at the rear end by a head 6 secured to the sternpost 40 of the ship in a manner similar to known screw propeller bosses. The body 1 is provided with webs or ribs 7 at one end and with a closing plate 8 at the other end and is supported upon a spindle 9 which runs 45 in bearings in the sternpost; a thrust-bearing (not shown) can, if considered necessary be provided to transmit the propelling power to the ship in a favourable manner. Into the casing of the propeller, which is 50 formed as a labyrinth packing 10, issues the pressure-water supply pipe 3.

Between the propeller body 1 and the packing ring 10 a rotating set of turbine blades 11 is arranged, which is combined 55 with a set of stationary guide blades 12 fixed on the pipe 3, and with covering ring 13, to form a water turbine (Fig. 2) which enables the propeller to be set in rotation in

the direction indicated by the arrow. A valve member 14 slidably supported in the 60 interior of the pipe 3 enables the turbine to be cut out, or brought into operation, according to requirements, and therewith a wide range of regulation from rearward 65 up to forward rotation of the propeller, the slide 14 being moved by means of any suitable operating device traversing the water pipe.

For rearward travelling either a suitable 70 separate propeller or a second group of exit slots may be provided together with a reversing slide on the forward propeller serving for alternately shutting off and bringing the same into operation.

I claim:

1. A ship's propeller of the fluid reaction type comprising in combination a water supply pipe, a hollow rotatable body of a cylinder-like shape and spirally formed water exit slots in the circumference of said body. 75

2. A ship's propeller of the fluid reaction type comprising in combination a water supply pipe, a hollow rotatable body of a cylinder-like shape, spirally formed water exit slots in the circumference of said body, and means for rotating said body in the manner of a usual ship's screw. 80

3. A ship's propeller of the fluid reaction type comprising in combination a water supply pipe, a hollow rotatable body of a cylinder-like shape, spirally formed water exit slots in the circumference of said body, and a water turbine connected to said body, so as to rotate it, and connected to said water supply pipe so as to receive driving water. 90

4. A ship's propeller of the fluid reaction type comprising in combination a water supply pipe, a hollow rotatable body of a cylinder-like shape and spirally formed water exit slots in the circumference of said body, the said water exit slots having inclined 100 passages rearwardly directed.

5. A ship's propeller of the fluid reaction type comprising in combination a water supply pipe, a hollow rotatable body of a cylinder-like shape and spirally formed water exit slots in the circumference of said body, the said water exit slots having inclined 105 passages rearwardly directed, and means provided on said body adapted to alter its rotating velocity or holding it stationary. 110

HANS WIEDEMANN.
